(57) **CLAIM**

The ornamental design for a food and feed industry machine (extruder) as shown and described.

DESCRIPTION

Figure 1.1 is a top view of a food and feed industry machine (extruder) according to our new design;

Figure 1.2 is a bottom view thereof;

Figure 1.3 is a front view thereof;

Figure 1.4 is a back view thereof;

Figure 1.5 is a right side view thereof;

Figure 1.6 is a left side view thereof; and

Figure 1.7 is a perspective view thereof.

The portions of the food and feed industry machine (extruder) shown in broken lines form no part of the claimed design.

1 Claim, 7 Drawing Sheets
